United States Patent

Des. 238,938
Patented Feb. 24, 1976

238,938

AIRCRAFT

Paul S. Moller, Dixon, Calif., assignor to
Discojet Corporation, Davis, Calif.

Filed Mar. 24, 1975, Ser. No. 561,234

Term of patent 14 years

Int. Cl. D12—07

U.S. Cl. D12—79

FIG. 3

FIG. 4

FIG. 1 is a plan view of an aircraft showing the design;
 FIG. 2 is a view from one side of the aircraft, the opposite side view being substantially the same but of opposite hand;

FIG. 3 is a view from below of the aircraft; and

FIG. 4 is a view from the rear of the aircraft, the view from the front being substantially the same.

I claim:

The ornamental design for an aircraft, as shown and described.
